UNITED STATES PATENT OFFICE.

WALTER B. ENGH, OF CHICAGO, ILLINOIS, ASSIGNOR TO THE MANTLE LAMP COMPANY OF AMERICA, OF CHICAGO, ILLINOIS, A CORPORATION OF ILLINOIS.

WICK.

Application filed January 27, 1922. Serial No. 532,301.

To all whom it may concern:

Be it known that I, WALTER B. ENGH, a citizen of the United States, residing at Chicago, in the county of Cook and State of Illinois, have invented certain new and useful Improvements in Wicks, of which the following is a specification.

The invention relates to wicks for lamps and analogous oil burning devices in which wicks are employed to raise the oil from a reservoir to the operative part of a burner.

Objects of the invention are to stiffen the wick so that it will not be deformed when inserted in the burner, or deformed by the thrust of the wick raiser when in use; to size the wick at the time of its production, so that it will easily move up and down upon the guiding inner wick tube of a burner without binding or undue resistance; to substantially confine the evaporation of the oil to a limited and chosen area of the wick; to make the wick-raising element of the wick which is attached thereto substantially an integral part of the wick, and to simplify and thereby cheapen the cost of the wick-raising devices.

The invention will be best understood if reference is made to the accompanying drawing, forming part of this specification, in which—

Figure 1 is a vertical sectional view of a burner embodying the invention;

Figure 2 is a perspective view of a wick containing my improvements;

Figure 3 is a cross-sectional view of the burner, taken on the line 3—3 of Figure 1, and

Figure 4 is an enlarged view of a portion of Figure 3 revealing the connection between the wick and an attached part of the wick raiser.

The wick 1 is of the woven variety wherein cotton fibers are associated in such manner as to admit of the required maximum feeding of oil to the burner, and this wick is disposed between an outer wick tube 2 and an inner wick tube 3, in the usual manner.

Surrounding the wick is a wick raising sleeve 4 having upwardly-extending flexible arms 5, each arm being provided with a hole 6 constituting the female member of a joint or union between the wick raiser and the wick. This sleeve and its arms constitute no part of the present invention.

The other member of the joint or union, is a knob-like piece of metal 7 having prongs 8 extending through the wick, and of sufficient length when bent, as at 9, to be guided by the outer surface of the inner wick tube 60 as the wick is raised or lowered, the contacting metallic surfaces of the prongs and the wick tube affording considerable ease in the manipulation of the wick-raising device even though the wick fits the inner 65 wick tube with a slight degree of looseness. The individual male members of the joint are conveniently cut from a single strip of metal produced in a machine especially constructed for that purpose, but they may be 70 made in any other manner, as deemed desirable.

The wick may be stiffened by adherent linings of woven fabric 10, or similar linings of paper 11, respectively shown in Figures 75 2 and 1. The lining of woven fabric may be a piece of cotton tape, such as is made with a water-soluble adhesive film on one side, and if paper be used it will have a similar adhesive film.

The wick may be stiffened with a reinforcing lining on one side only, however I prefer to use linings for sections of both the inside and outside of the wick especially at points where the wick raising mechanism 85 is attached. Other sections of the wick may be stiffened by being coated with an aqueous solution containing a phenol or cresol and formaldehyde, or other suitable stiffening substance, but stiffening the wick in this latter manner constitutes, per se, no part of the present invention.

When adhesive tape is used for a reinforcing lining, it should have a gummed surface film and be about five thousandths of 95 an inch in thickness. The tape is first formed into a cylinder over an arbor, with the gummed side out, and the wick is then pulled over the tape cylinder while it is still on the arbor. This operation forms the 100 inside lining for the wick. The wick thus mounted is then steamed and dried until the tape firmly adheres to the wick. As these operations are done over an arbor of a definite size, it is possible to obtain a wick 105 of a desired internal diameter which will fit around an inner wick tube in a uniform manner, and with the required degree of looseness. While the wick, with the inside lining in position is still on an arbor, a sec- 110

tion of the outside of the wick may be reinforced by wrapping with a gummed tape. I find it preferable to reinforce with a woven tape a section of the outside of the wick to thereby form a more rigid seat for the metal mounting 7 and to determine a closure to the upper end of the slot of a bifurcated wick.

In addition to the above-stated advantages following the use of the tape lining 10 of the wick, a further advantage is found in the relative impermeability of the tape which reduces the amount of oil at the hot surface of the inner wick tube, and, to a certain extent, prevents the excessive evaporation which interferes with the production of a blue heating flame. A further advantage attending the use of the tape lining, is that said lining maintains the regularity and even shape of the tip of the wick, a 20 result which cannot be attained in wicks wherein the fabric at the inside of their tips is without re-inforcement. In such wicks, the fibers of the woven material become disarranged at the wick tips, and do not uniformly feed the oil in equal quantities at all 25 parts of the circumference to thereby produce a symmetrical flame. In consequence of this irregularity of feeding, the flame is irregular and incapable of heating all parts 30 of the mantle of a lamp to the same degree of incandescence.

Having thus described my invention, what I claim is:

1. A wick comprising a capillary element 35 of tubular form, and a sized re-inforcing layer of cellulose adherently secured to the inner wall thereof.

2. A wick comprising a stiffened flexible capillary element composed of cellulose, and

a layer of cellulose adherently secured to a 40 wall thereof.

3. A wick comprising a flexible capillary element composed of cellulose impregnated with a stiffening substance, and a layer of cellulose adherently secured to a wall 45 thereof.

4. An annular wick having the upper portion of its inner wall covered by a tape secured to said wall by an adhesive substance.

5. An annular wick having an inner lining of relatively-low capillarity, and an outer covering of relatively-low capillarity extending upward to a point below the tip thereof.

6. An annular wick stiffened and sized by an adherent tape.

7. A wick combined with separate complementary clip members secured to the outside thereof and adapted to engage a wick 60 raiser.

8. A wick combined with members of a wick-raising mechanism, said members being provided with penetrative prongs and adapted to engage the actuating means of 65 said wick-raising mechanism.

9. The combination with a wick tube, of a wick surrounding said tube, wick-raising elements, and penetrative points carried by said elements and extending through the 70 wick to and into contact with said wick tube.

10. A tubular wick composed of cellulose material, and including an inner layer for stiffening and sizing the interior and an outer layer for stiffening and sizing the exterior thereof.

In testimony whereof I affix my signature.
WALTER B. ENGH.
